UNITED STATES PATENT OFFICE.

LEON COHEN, OF ST. LOUIS, MISSOURI.

HAT PAD.

Application filed October 19, 1925. Serial No. 63,279.

My invention relates to improvements in hat pads, and has for its primary object a hat pad designed to be placed within the head receiving opening of a hat for the purpose of reducing the size of the same; the pad being so constructed as to readily conform to the head and make the hat fit snugly without exerting any great degree of pressure on the head.

10 A further object is to construct a heat pad which is hollow and so arranged that when a hat having one of these devices attached thereto is placed on the head of the wearer, a certain amount of the air contained in the 15 casing is permitted to escape from the casing and on removing the hat fresh air is again drawn in. By this construction, the hat pad will be continuously filled with fresh air and will be much cooler on the head of the 20 wearer than is a pad which is filled with fibrous material.

My improved pad is of the self attaching type and is so constructed that no stitching or sewing is necessary.

25 In the drawings:

Fig. 1 is a top plan view of my device;

Fig. 2 is a longitudinal section taken on the line 2—2 of Fig. 3;

30 Fig. 3 is a face view of the same looking in the direction of the arrow 2 in Fig. 1;

Fig. 4 is an enlarged cross section taken on the line 4—4 of Fig. 1;

Fig. 5 is an enlarged cross section taken on the line 5—5 of Fig. 1; and

35 Fig. 6 is a perspective view of one of the securing prongs employed.

In the construction of my device, I employ a strip of metal 7, which is preferably of spring material. This strip is preferably 40 provided with laterally extending spaced apart kinks 8, by means of which the strip is given an arcuate shape. Secured to the strip 7 at spaced apart intervals are sleeves 9, which have extending therefrom fastening 45 prongs 10; the position of these prongs on the strip being clearly shown in Figs. 1 and 2. 11 represents a strip of elastic material which is slightly wider than the strip 7. The ends of the strip 11 are brought around 50 the ends of the strip 7 and passed over the fastening prongs located at each end of the strip. The length of the elastic strip 11 is less than the strip 7. The purpose of this will be explained in detail later. Secured around or encasing the strips 7 and 8 is a 55 casing 12. This casing is preferably very

closely woven fabric so that it will not readily permit the escape of air therethrough. The casing is substantially crescent shaped. By this construction of casing the longitudinal edges 13 of the strip 11 will be turned inside as illustrated in Fig. 4 thus leaving the major portion of the inside or concave face of the pad convexed laterally also and by reason of the elastic strip 11 being of less length than the strip 7 an air pocket 14 will be formed between the strips 7 and 11. It will be noted from Fig. 5 that the edges 13 of the elastic 11 are bent over the strip 7 thereby gradually making the 70 pad taper out flat at each end. The purpose of kinking the strip 7 is to give it an arcuate shape and permit it to more readily conform to the inside of a hat crown because the kinking will permit the strip to 75 bend readily along these kinks and it will, therefore, not have the tendency to force the hat crown out of shape as would be the case where the bending of the strip is by sheer force.

80 My device is preferably applied to the rear portion of the hat and is of such length as to extend less than completely around the interior of the hat crown. In applying my device, the lower edge of the pad is placed 85 along the lower edge of the head receiving opening of a hat crown and the prongs pushed through the crown. This is all that is necessary to hold my device in position because the curvature of the metal strip 7 90 is greater than the curvature of the head receiving opening so that there will be sufficient tension set up in this strip when applying the device to cause it to have a tendency to spring outward sufficiently to hold the 95 prongs in place. After the device has been placed in position and when putting on the hat, the elastic strip 11, which extends across the head receiving opening, will be 100 stretched and forced toward the strip 7, thus reducing the size of the air pocket 14, compressing the air therein and forcing it out through the closely woven fabric.

105 It will also be noted from my construction that there will be no sharp edges along that portion of the pad which contacts with the head and, therefore, it will cause no discomfort to the wearer.

I do not desire to limit myself to the precise construction of securing prongs as illustrated as the prongs may be attached to the strip in various other ways, or they may 110

also be stamped out integral with the strip 7. This latter feature is not shown as it is well known in the metal stamping art.

Having fully described my invention, 5 what I claim is:—

1. A hat pad comprising an arcuate flexible flat strip, fastening prongs projecting from the convex face thereof, an elastic of less length than said strip and of greater 10 width than said flexible strip having its ends secured to said flexible strip whereby said strip is bowed outwardly from said elastic strip, a fabric covering for said strip and said elastic for drawing in said elastic so as 15 to concave the same and place it under tension, said covering also adapted to bend the longitudinal edges of the elastic strip toward the flexible strip whereby a laterally convex face is formed along the elastic strip 20 throughout the major portion of its concave face.

2. A hat pad comprising an elongated

strip of spring material having laterally extending kinks formed therein so as to curve 25 the same longitudinally and without setting up any strain therein, fastening prongs projecting from the convex face thereof, an elastic of less length than said strip and of greater 30 width than said flexible strip having its ends secured to said flexible strip whereby said strip is bowed outwardly from said elastic strip, a fabric covering for said strip and said elastic for drawing in said elastic so as to concave the same and place it under 35 tension, said covering also adapted to bend the longitudinal edges of the elastic strip toward the flexible strip whereby a laterally convex face is formed along the elastic strip 40 throughout the major portion of its concave face.

In testimony whereof I have affixed my signature.

LEON COHEN.
